J. E. CHALMAN.
GUIDE FOR SEWING MACHINES.
FILED DEC. 21, 1917.

3 SHEETS-SHEET 3

UNITED STATES PATENT OFFICE.

JOHN E. CHALMAN, OF CHICAGO, ILLINOIS, ASSIGNOR TO UNION SPECIAL MACHINE COMPANY, OF CHICAGO, ILLINOIS, A CORPORATION OF ILLINOIS.

GUIDE FOR SEWING MACHINES.

Application filed December 21, 1917. Serial No. 203,278.

To all whom it may concern:

Be it known that I, JOHN E. CHALMAN, a citizen of the United States, residing at Chicago, in the county of Cook, State of Illinois, have invented certain new and useful Improvements in Guides for Sewing Machines, of which the following is a description, reference being had to the accompanying drawing and to the figures of reference 10 marked thereon.

The invention relates to new and useful improvements in guides for sewing machines and more particularly to a guide which may be used for overlapping the fabric sections 15 and directing the same to a stitch forming mechanism.

In the stitching of heavy materials such as for tents or the like, it is desirable that the large and extensive parts of the tents pass 20 the stitching mechanism outside of the line of feed, while the smaller parts which are being joined to the larger parts, pass beneath the overhanging arm of the machine or inside the line of feed. It is also desirable that 25 the sections being stitched overlap each other in a certain desired relation; sometimes the inner or smaller section should overlap the outer or extensive section, while in other instances, the smaller section should underlie 30 the outer or extensive section, as the parts are stitched.

An object of the present invention is to provide a guiding mechanism for overlapping fabric sections which are to be stitched, 35 which guiding mechanism may be quickly reversed so that the inner section may be caused to overlie the outer section or underlie the outer section as the operator desires.

A further object of the invention is to 40 provide a guiding mechanism of the above character wherein the parts are adjustable so that one section may be caused to overlap the other section to a greater or less extent and the edges of both sections may be 45 shifted transversely of the line of feed for varying their position relative to the needles which stitch the sections together.

These and other objects will in part be 50 obvious and will in part be hereinafter more fully disclosed.

In the drawings, which show by way of illustration, one embodiment of the invention,—

Figure 1 is a front view of a portion of

a sewing machine having my improved 55 mechanism applied thereto;

Fig. 2 is a view partly in plan and partly in section, with the fabric sections broken away to show the relation of the presser foot and the sewing mechanism to the strip 60 guiding and feeding mechanism;

Fig. 3 is a sectional view along the line of feed, but showing the guiding device in end elevation;

Fig. 4 is a perspective view of my improved guiding device and the supporting plate therefor;

Fig. 5 is a sectional view on the line 5—5 of Figure 2, but with the fabric in position for guiding;

Fig. 6 is a plan view of the guiding device and supporting plate therefor showing the guiding device reversed from the position shown in Fig. 2;

Fig. 7 is a diagrammatic view, showing 75 the fabric sections overlapped by the guide when positioned as shown in Fig. 5;

Fig. 8 is a similar view but showing the fabric sections as overlapped when the guide is positioned as shown in Fig. 6. 80

I have shown my improved guiding mechanism as applied to a sewing machine having a work support 1, an overhanging arm 2, in which a needle bar 3 reciprocates. Mounted on the needle bar are two spaced 85 needles 4 and 5. Co-operating with the needle 4 beneath the work support is a looper 6. Co-operating with the needle 5 is a looper 7. The material is held on the work support by a presser foot 8, carried by a 90 presser bar 9 supported by the overhanging arm 2. The material is fed across the work support by a feed dog 10 mounted on a feed bar 11 and operated in the usual manner.

My improved device consists of a supporting plate 12 which is provided with slots 13 and 14 adapted to receive screws 15 and 16 respectively, which pass into the work support 1 and hold the plate fixed thereto. Mounted on this plate is an edge guiding 100 member 17. Said edge guiding member 17 is fixed to a post 18 which extends through the plate 12 and an opening 19 in the work support 2. A spring 20 surrounds this post and bears at its upper end against the plate 105 12. The lower end of the spring bears against a washer 21 which is held to the post 18 by a headed screw 22. The purpose of

this spring is to yieldingly press the guiding member 17 against the plate 12. This guiding member 17 has an overhanging ledge 23 thus forming a guiding recess 24 which is 5 adapted to receive the fabric section which is guided thereby to the stitching mechanism. The vertical end wall 25 guides the edge of the fabric section. Mounted on the overhanging ledge 23 is a plate 26 which is provided with an upturned wall 27. This upturned wall 27 serves as an edge guide for the other section of fabric, the edge thereof passing along said wall. Said plate 26 is formed with slots 28-28 and screws 15 29^a-29^a, passing through said slots into the overhanging ledge 23, secure this upper guiding member formed by the plate 26 and the wall 27 in an adjusted position.

The guiding member 17 is formed with 20 a downwardly projecting pin 48 which is adapted to engage an opening 29 in the plate 12 and when reversed from the position shown in Fig. 5, said pin is adapted to engage an opening 30 in said plate. This pin 25 serves to hold the guiding member in position for directing the fabric sections.

The materials being stitched consist of an outer section M which may be the large extensive section of a tent or the like, and an 30 inner section M', which may be a smaller strip which is to be stitched to this outer section. In some instances it is desirable to cause the strip M', to overlap the outer section M, as shown in Fig. 7. For this purpose, the guide is set as shown in Figs. 1, 2, 3 and 5, and as the fabric sections pass through the guide they will be overlapped in the manner stated. In Figs. 7 and 8 of the drawings, I have shown at N and N' the 40 lines of stitching formed by the needles 4 and 5 respectively. The needles are widely spaced and the guides will set so that the lines of stitching pass through the fabric sections adjacent the extremes of the overlapped portions. It is sometimes desirable to cause the strip M' passing underneath the overhanging arm to underlie the outer or extensive section M. For this purpose the operator merely lifts the guiding member 17, 50 freeing the pin 48 from the opening 29 and turns the same about the post 18 as a pivot until the pin 48 is brought into register with the opening 30. It is then released and the spring will cause said pin to engage the 55 opening and hold the guide in this position. The section M is then guided by the vertical wall 27, while the section M' is then guided by the vertical wall 25.

By shifting the plate 12 laterally through 60 loosening the screws 15 and 16, the position of the guiding wall 25 relative to the needles may be varied. After this wall has been properly set to cause the needle to pass at the desired distance back from the edge of 65 the underlying strip then the plate 26 may

be adjusted by loosening the screws 29^a so as to properly position the edge of the overlying strip relative to the needles.

From the above it will be apparent that I have provided a guiding device for overlapping fabric sections which may be adjusted so as to shift the positions of the overlapped sections or vary the extent of the overlap and which guiding means can also be quickly shifted so as to cause either 75 section desired to overlap the other section.

It is obvious that minor changes in the details of construction and arrangement of parts may be made without departing from the spirit of the invention as set forth in the 80 appended claims.

Having thus described my invention, what I claim as new and desire to secure by Letters Patent, is:—

1. A guiding device for overlapping fabric 85 sections including in combination, a supporting plate, guiding walls for directing the respective fabric sections in overlapped relation to each other, and means for permitting the guiding walls to be shifted so 90 as to cause either section to overlap the other.

2. A guiding device for overlapping fabric sections including in combination, a supporting plate, a guiding member having a guiding wall for one of the fabric sections, means 95 for pivotally supporting said guiding member on said plate, for permitting the same to be shifted to cause its guiding wall to face in either direction longitudinally of the plate, and a second guiding wall carried by 100 said guiding member for guiding a section in overlapped relation to the section passing along the first named guiding wall.

3. A guiding device for overlapping fabric sections, including in combination, a supporting plate, a guiding member having guiding walls for directing fabric sections in overlapped relation to each other, a depending post on which said guiding member is mounted, said depending post 105 extending downwardly through said plate, a spring surrounding said post and yieldingly pressing said guiding member against the plate, said plate having openings formed therein on opposite sides of said supporting 110 post, said guiding member having a pin adapted to engage either opening whereby the guiding device may be caused to face in either direction longitudinally of said 115 plate.

4. A guiding device for overlapping fabric sections, including in combination, a supporting plate, a guiding member having a guiding recess, a depending post on which said guiding member is mounted, said depending post extending downwardly through said plate, a spring surrounding 125 said post and yieldingly pressing said guiding member against the plate, said plate having openings formed therein on opposite sides of 130

said supporting post, said guiding member having a pin adapted to engage either opening whereby the guiding recess may be caused to face in either direction longitudinally of said plate, a plate having a vertical wall for directing the edge of a section in overlapped relation to the section passing through the guiding member, said plate being secured to said guiding member and 10 shiftable therewith.

5. A guiding device for overlapping fabric sections including in combination, a supporting plate, a guiding member having guiding walls for directing fabric sections in overlapped relation to each other, a depending post on which said guiding member is mounted, said depending post extending downwardly through said plate, a spring surrounding said post and yieldingly pressing 20 said guiding member against the plate, said plate having openings formed therein on opposite sides of said supporting post, said guiding member having a pin adapted to engage either opening whereby the guiding device may be caused to face in either direction longitudinally of said plate, and means whereby said plate may be attached to the work support of a sewing machine so that said plate may be adjusted in a direction at right angles to the line of feed, a plate adjustably secured to the guiding member whereby the same 30 may be shifted in a direction at right angles to the line of feed of the sewing machine, said plate having an upturned edge for directing the overlapping fabric edge passing through the guiding device. 55

6. A guiding device for overlapping fabric sections, including in combination, a supporting plate, a guiding member having a guiding recess, a depending post on which 35 said guiding member is mounted, said depending post extending downwardly through said plate, a spring surrounding said post

and yieldingly pressing said guiding member against the plate, said plate having openings formed therein on opposite sides 40 of said supporting post, said guiding member having a pin adapted to engage either opening whereby the guiding recess may be caused to face in either direction longitudinally of said plate, and means whereby said plate may be attached to the work support of a sewing machine so that said plate may be adjusted in a direction at right angles to the line of feed, a plate adjustably secured to the guiding member whereby the same 50 may be shifted in a direction at right angles to the line of feed of the sewing machine, said plate having an upturned edge for directing the overlapping fabric edge passing through the guiding device. 55

7. A sewing machine guide for overlapping fabric sections including in combination, a guiding device having a recess for receiving and guiding the edge of one fabric section, a second guiding device attached to the first named guiding device and having a wall for guiding the edge of a second fabric section in overlapping relation to the edge of the first mentioned section, and means for permitting said guiding devices 60 to be shifted so as to cause either section to overlap the other. 65

In testimony whereof, I affix my signature, in the presence of two witnesses.
